US0D1042384S

(12) **United States Design Patent** (10) **Patent No.:** **US D1,042,384 S**
(45) **Date of Patent:** **** Sep. 17, 2024**

(54) **DISPLAY DEVICE**

(71) Applicant: **Samsung Display Co., Ltd.**, Yongin-si (KR)

(72) Inventors: **Ho Yeon Yu**, Yongin-si (KR); **Hyun Gu Kim**, Yongin-si (KR); **Sungsu Park**, Yongin-si (KR)

(73) Assignee: **Samsung Display Co., Ltd.**, Yongin-si (KR)

(**) Term: **15 Years**

(21) Appl. No.: **29/853,632**

(22) Filed: **Sep. 16, 2022**

(30) **Foreign Application Priority Data**

Mar. 16, 2022 (KR) 30-2022-0010237

(51) **LOC (14) Cl.** **14-03**

(57) **CLAIM**

The ornamental design for a display device, as shown and described.

DESCRIPTION

FIG. 1 is a perspective view of a display device showing the new design, shown in a folded configuration;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a perspective view of the display device in an unfolded configuration;

FIG. 9 is a front view thereof;

FIG. 10 is a rear view thereof;

FIG. 11 is a left side view thereof;

FIG. 12 is a right side view thereof;

FIG. 13 is a top view thereof;

FIG. 14 is a bottom view thereof;

FIG. 15 is a front view of the display device in a folded and extended configuration; and,

FIG. 16 is a front view of the display device in an unfolded and extended configuration.

The broken lines in the figures depict portions of the display device that form no part of the claimed design.

1 Claim, 16 Drawing Sheets
